Specification for Design.

Patented July 18, 1922.

Application filed December 27, 1921. Serial No. 525,250. Term of patent 14 years.

To all whom it may concern:

Be it known that I, WILLIAM OCHSE, a citizen of the United States, residing at the city of San Antonio, State of Texas, have invented a certain new, original, and ornamental Design for a Combination Watch and Knife or Article of Similar Nature, of which the following is a specification, reference being had to the accompanying drawing, forming a part thereof.

The drawing illustrates a combination

watch and knife, or article of similar nature embodying my new design, Figure 1 being a rear elevational view, Figure 2 being a plan view, and Figure 3 being a front elevational view.

I claim:

The ornamental design for a combination watch and knife, or article of similar nature, substantially as shown.

WILLIAM OCHSE.
